UNITED STATES PATENT OFFICE.

ALEXANDER BERNHARD DRÄGER, OF LUBECK, GERMANY; ELFRIEDE DRÄGER, NÉE STANGE, EXECUTRIX OF SAID DRÄGER, DECEASED.

SELF-CONTAINED LUNG-POWER BREATHING DEVICE.

Application filed November 15, 1922, Serial No. 601,030, and in Germany December 10, 1921.

The present invention relates to a self-contained breathing device having a circuit system for the flow of the breathing air and comprising essentially an air purifying cart-
ridge, a valve casing containing suitable breathing valves and ducts, an inhaling and an exhaling flexible breathing tube, an oxygen cylinder and a breathing bag; and more particularly refers to improved means in connection and cooperation with the said device in order to provide the same with that amount of oxygen necessary for the actual breathing requirements of the user of the device, and to obviate at the same time any overcharging of the breathing air with nitrogen.

There have already become known self-contained breathing devices in which a certain constant amount of oxygen (say about 1.2 litres per minute) is supplied into the air circuit system by means of a pressure reducing valve and in which besides that an additional amount of oxygen may be supplied by means of a manually actuated pressure but-ton valve or the like of a by-pass conduit during the working periods which require a greater amount of oxygen. In these devices the flow of oxygen is to a certain degree at will and dependent on the practice of the operator. The danger with which these devices are afflicted and to which the users of such devices are constantly subjected, consists in the accumulation of nitrogen within the breathing bag in case the oxygen used is not pure, that is to say, contains more than one half to one per cent of nitrogen. This danger of overcharging the air with nitrogen may however be restricted or avoided by a frequent operation of the said by-pass valve in order to supply additional oxygen into the breathing bag or respectively to rinse the same by such additional oxygen. When the accumulation of nitrogen, that is to say, the overcharging of the air with nitrogen is to be avoided principally, a greater constant supply of oxygen, say from 1.5 to 1.8 litres per minute, must be chosen from the very beginning. In such a case the user of the device is receiving constantly an excess of breathing air and is compelled to empty the breathing bag from time to time whereby the nitrogen accumulated therein is expelled together with a certain amount of oxygen which gets lost for the respiration. This loss of oxygen, due to untimely operating the by-pass

valve for additional oxygen supply or to a too great constant oxygen supply, may sometimes be very considerable and forms a great drawback of this type of devices, which must therefore be furnished with greater oxygen cylinders whereby furthermore the total weight of the device will materially be increased.

There are also known self-contained breathing devices with a lung-automatic oxygen supply such as described in my prior Patent No. 1,610,760, Dec. 14, 1926. In these devices there is arranged a lung-automatic oxygen supply contrivance, for example, an auxiliary breathing bag adapted to open a self-closing valve mechanism of the oxygen supply pipe at the slightest sucking action in the air circuit system of the breathing device. The necessary sucking action takes place at the time and as often as the main breathing bag is fully emptied by inhalation which will occur at about every sixth inhaling breath. The admission of oxygen takes place whenever the auxiliary bag or the valve mechanism is operated and that so quickly and so abundantly that the lungs can fill themselves automatically according to the needs of respiration. It is due to the nature of the function of this breathing device that the stock of air in the main breathing bag is at no time greater than the capacity of the lungs and that the said device must be worked with oxygen of high percentage and free from nitrogen, in order to obviate the dangerous overcharging of the air in the main breathing bag and the lungs with nitrogen. The special advantage of this breathing device which certainly compensates the drawback of a temporary vacuum in the air circuit system, is to be seen in that oxygen can get lost at no time, not even when the stop valve of the oxygen cylinder has been left open by inadvertence.

The improved breathing device forming the subject-matter of the present invention has come into existence by combining the two breathing devices above commented upon. This combination is entirely new and produces a device which keeps up the advantages of the said two known breathing devices, but precludes the drawbacks of the same, and with this end in view my improved self-contained breathing device consists in certain novel features of construction and combinations of parts as will be hereinafter

fully described and pointed out in the claim with reference to the accompanying sheet of drawings in which:

Fig. 1 is a diagrammatic view of a self-contained breathing device with lung-automatic oxygen supply constructed in accordance with and embodying a preferred embodiment of the invention, and

Fig. 2 a similar view showing a modification of the device.

Similar letters of reference designate like parts throughout the figures.

To the breathing conduit *b* (Fig. 1) of the device is connected at *d* a breathing bag *s* of any approved construction. From the low pressure compartment of the pressure reducing valve *g* connected to the oxygen cylinder *f* by a high pressure pipe *e*, a pipe *a* leads to the conduit *b* and another pipe *c* to a hose-shaped flexible auxiliary or supplemental bag *i* the other end of which is connected to a socket *b*¹ of the conduit *b*. In using the device a certain amount of oxygen, about 1 litre per minute, is constantly passing through the pipe *a* into the air circuit system of the device. This amount of oxygen is not sufficient for ordinary breathing requirements. The deficiency of oxygen is automatically admitted by the supplemental bag according to the needs of respiration. This supplemental bag *i* with the aid of a control device located inside the supplemental bag *i* automatically regulates a suitable self-closing stop valve *x* of the oxygen supply pipe *c* to permit the flow of a greater or lesser quantity of oxygen into the supplemental bag *i* and from there into the air circuit system of the breathing device. According to the type shown the control device consists of a fixed plate *r* and a movable plate *t* both of which are conveniently shaped to the length of the supplemental bag and together form a sort of flat beak, which is kept in an open or distended position through the operation of a spring *u* located between the beak-parts *r* and *t*. When the movable plate

t is rocked against the fixed plate *r* due to a contracting or collapsing of the supplemental bag *i* caused by want of air in the main breathing bag *s*, the stop valve *x* is opened accordingly to supply instantaneously the requisite quantity of additional oxygen.

In the modification shown by Fig. 2 the additional oxygen is taken from the high pressure pipe *e*; the supply pipe *c* controlled by the stop valve *x* being connected directly to the pipe *e*. In this case the additional oxygen supplied automatically by the lung-power, does not take its way through the pressure reducing valve *g*.

I claim:

A self-contained breathing device adapted to prevent the breathing air from being overcharged with nitrogen, comprising in combination an air circuit system, a collapsible breathing bag in said system, an oxygen container, a reducing valve, a high-pressure connection from said container to the inlet side of said reducing valve, a continuously open connection from the outlet side of said reducing valve to said air circuit system constructed and arranged to continuously pass oxygen for revivifying the breathing air into said system in a predetermined constant amount per unit of time and an oxygen supply controlling device connected directly with said reducing valve connection and with said breathing bag independently of said continuously open connection and automatically operated by inspiration whereby additional oxygen is periodically supplied to the air circuit system in accordance with the breathing requirements prevailing at the time, said device comprising an auxiliary breathing bag having a collapsible wall, the said wall having a substantial area exposed to the atmosphere, a movable member therein adapted to be actuated by movement of said wall, and a valve controlled by said movable mem- 90

ALEXANDER BERNHARD DRÄGER.
